UNITED STATES PATENT OFFICE

ALFRED G. KINTZ, OF WALLINGFORD, CONNECTICUT, ASSIGNOR TO INTERNATIONAL SILVER COMPANY, OF MERIDEN, CONNECTICUT, A CORPORATION OF NEW JERSEY

DESIGN FOR A SPOON OR SIMILAR ARTICLE

Application filed August 28, 1929. Serial No. 32,580. Term of patent 14 years.

To all whom it may concern:

Be it known that I, ALFRED G. KINTZ, a citizen of the United States, residing at Wallingford, county of New Haven, and State of Connecticut, have invented a new, original, and ornamental Design for a Spoon or Similar Article, of which the following is a specification, reference being had to the accompanying drawing, forming a part thereof.

Fig. 1 is a front view of a spoon or similar article, showing my new design.

Fig. 2 is a back view of the same;
Fig. 3 is a side view of the same; and
Fig. 4 is a cross-section taken near the end of the handle at the line A—B.

I claim:

The ornamental design for a spoon or similar article, as shown.

ALFRED G. KINTZ.
